UNITED STATES PATENT OFFICE

167,256

BOX CAMERA

Arthur H. Crapsey, Jr., Rochester, N. Y., assignor
to Eastman Kodak Company, Rochester, N. Y.,
a corporation of New Jersey

Application April 8, 1952, Serial No. 19,240

Term of patent 7 years

(Cl. D61—1)

To all whom it may concern:

Be it known that I, Arthur H. Crapsey, Jr., a citizen of the United States of America, residing in Rochester, in the county of Monroe and State of New York, have invented a new, original, and ornamental Design for a Box Camera, of which the following is a specification, reference being had to the accompanying drawings, forming a part thereof in which:

Fig. 1 is a perspective view showing the front, the top wall and one end wall of a box camera illustrating my new design;

Fig. 2 is a perspective view showing the back, a portion of the top wall and the opposite side wall of the camera shown in Fig. 1;

Fig. 3 is a top plan view of the camera shown in the preceding figures; and

Fig. 4 is a bottom plan view of the camera shown in the preceding figures.

I claim:

The ornamental design for a box camera, as shown.

ARTHUR H. CRAPSEY, JR.
